UNITED STATES PATENT OFFICE

2,009,201

GASEOUS ELECTRIC DISCHARGE DEVICE

Marcello Pirani and Kurt Nitschke, Berlin-Wilmersdorf, Germany, assigns to General Electric Company, a corporation of New York

Application July 25, 1929, Serial No. 381,036
In Germany August 1, 1928

2 Claims. (Cl. 176—125)

The present invention relates to gaseous electric discharge devices.

Heretofore, electric discharge tubes with a filling of common gases, such as carbonic acid gas, nitrogen, hydrogen, because of the quick clean up of such gases under a low pressure of gas filling, have been provided with a floating valve for automatically feeding needed gas replenishments into the tube. Such a floating valve in shipment of the tube is easily deranged and rendered ineffective, and, further, much space is taken up by the gas generators such as the containers for the hydrochloric acid and marble dust in the generation of carbonic acid gas and the readily ignitable phosphorus used in the generation of nitrogen, and for these reasons, it has been proposed recently to mount such gas replenishing materials either in an offset of the discharge tube or in a hollow space in the electrodes of said discharge tube. Such materials are, for example, magnesium carbonate, sodium azide, lithium hydride, and these are heated by the operation of the tube itself. That is, when the current density exceeds a predetermined value the gas evolving material is heated, gas is evolved and the gas content of the tube is replenished. In these devices the gas evolving material is constantly subjected to heat radiated from the positive column of the discharge, or the radiations from the electrodes, or from a heater wire connected in series with the light tube circuit. In all these methods, in spite of the most careful measuring of the quantity of the gas evolving material and the surfaces of the containing chamber, it sometimes happens that the gas pressure in the tube, in the course of time, mounts to a disadvantageous degree during the operation of the device.

The object of this invention is to avoid the over-supply of gas into the electric discharge device. For this purpose, the gas producing material, during the operation of the device, is heated by an electric heating means (heater wire, heat mantel or heat ring) automatically put in the circuit when the current density of the tube exceeds a predetermined value. The invention attains its object by maintaining the gas evolving material inactive under normal operating conditions and instantly, as soon as the current density of the tube exceeds a predetermined value, the heating means starts the gas evolution. For the purpose of putting the heating means into the circuit when the tube current density becomes high an electro-magnet connected to one of the current leads of the electric discharge device is used. The core of said electro-magnet acts as the circuit closing de-

vice of the heater circuit and is connected to the primary or secondary of the tube transformer.

By the use of the above described new method and apparatus only a very short heating of the gas evolving material takes place with a consequent quick evolution of gas. This is advantageous in practice, as the gas evolving material need not, unless desired, be placed in the interior of the tube, likewise there is no necessity for a heating container in which is placed in pulverized form the gas evolving material as said material may now be used in the shape of a rod heated by a surrounding or imbedded heating wire filament or else a heat mantel. The said rod is made by suitably pressing pulverized gas evolving material and then sintering it. Many of the pulverized gas feeders, for example magnesium carbonate, are, however, in large part decomposed during the sintering operation and hence such rods prepared by the old methods give off little or no gas in the operation of the tube. I have discovered that this condition is remedied when the rod shaped body comprises a mixture of pulverized gas evolving material and a material having a lower sintering point than the gas evolving material, for example, pulverized glass or enamel and used as a sintered binding material. After the mixture has been pressed into shape it is sintered at the lower sintering temperature of the binding material. In this sintering process the pulverized, contained particles of the gas emitting material are not used up as has been the case heretofore.

In Figs. 1 and 2 of the drawing are shown two circuits for the new light tube, and

Fig. 3 shows an alternative embodiment with the gas evolving material contained in an offset chamber.

The light tube as shown in Fig. 1 consists of a cylindrical chamber 1 of any desired glass or else of a glass which permits the passage of ultra-violet rays, and at each of its ends are mounted inner electrodes 2, or outer electrodes may be used. The tube 1 can be filled exclusively with a common gas, for example, carbonic acid gas, nitrogen, or hydrogen or else also with a mixture of suitable common gases with a rare gas or gases, for example neon, helium, argon, crypton, xenon. Both the electrodes 2 are connected by leads 3 to the secondary winding 4 of a transformer, the primary winding 5 of which is connected with a suitable current supply through a resistance 6.

In series in one of the current leads 3 of the tube 1 is an electro-magnet 7, the core 8 of which

carries a conducting plate 9, which bridges the contacts 10, 10. To these contacts are connected leads 11, 11 which are connected to a wire 12, made of high melting point metal such as chrome nickel, platinum, etc., sealed into a small offset chamber 13 of the tube 1, to heat rod 14. The latter together with the heating wire 12 can be sealed into the interior of the light tube 1 or else as shown, into a very small chamber 13 of the light tube. The rod 14 consists of a mixture of a gas evolving material and a material which can be sintered at a lower temperature than the decomposition temperature of the gas emitting material. As the gas evolving substance for supplying the light tube with carbonic acid gas, nitrogen, or hydrogen, I use, magnesium carbonate, calcium carbonate, sodium or barium azide, sodium or barium nitride or lithium hydride. Pulverized glass or pulverized enamel can be used as the low temperature sintering binding material for said gas evolving compounds. In the manufacture of the gas evolving rods the pulverized materials after thorough mixing are pressed into rod shape and heated up to the sintering point of the binding material. The pulverized particles of the gas evolving material thus become attached to each other without change of physical or chemical condition. By sintering the rods it is possible to drive off a part of the occluded gases in the rod with safety, and to prevent the remainder from entering into gas forming contamination in the rod, the sintering and the subsequent cooling taking place in a container which is either evacuated or else in which a continuous stream of the same gas is maintained as that which is given off by the gas evolving material in the rod when the rod is heated to a higher temperature.

With common gases present in the tube 1, at normal pressure and with normal current flowing through the tube, current does not pass through heater 12, as the core 8 is not raised. Therefore, under normal starting conditions the contacts 10 are bridged by conducting plate 9 of the electromagnet core 8 and the heater circuit 11, 12, is short circuited and the current discharge starts only between electrodes 2. During operation of the tube 1, should the gas pressure go down to a predetermined point and the current density of the tube rise correspondingly, the core of the electro-magnet 7, 8, is drawn up with a consequent raising of the plate 9 from the contacts 10. Current then flows through the heater wire 12, and, as a consequence, the rod 14 is heated and now gives off gas, until the pressure of the gas filling of the tube and the current through the tube have reached normal operating conditions. As soon as these conditions are reached the core 8 instantly falls again to its rest position on the contacts 10, 10 cutting out the heater.

While in the circuit control shown in Fig. 1 the heater circuit is connected to the secondary winding of the transformers, it is possible to connect the heater circuit as in Fig. 2 to the primary winding of the transformers. In this case also the winding 1 of an electro-magnet 7, 8 is connected in series with the lead 3 of the light tube; and the core 8 carries a current conducting plate 9. In this case, however, the contacts 10 are connected across leads 15, 15 of the transformer primary by leads 16, 16. In this embodiment, the contacts are open and current flows only to the electrodes 2 of the tube under normal conditions. The rising of the current density in the

tube again causes the actuation of the core 8 of the electro-magnet 7, 8 so that the plate 9 bridges the contacts 10, which closes the heater circuit 12, 16, which then operates in the same manner as the circuit described in Fig. 1.

To produce a slow and gradual diffusion of the replenishing gas which starts immediately upon the closing of the heater circuit of the gas evolving material, a tube 18 can, as shown in Fig. 3, be sealed in the connecting part 17 between the light tube 1 and the off-set chamber 13 which contains the gas evolving rod 14. The tube 18 is open only toward the interior of the light tube 1 and, therefore, acts as a dividing body between light tube 1, and offset chamber 13. This tube 18 is surrounded by winding 19 in series with the heater wire 12 and is heated therefore simultaneously with the rod 14, when the gas pressure in the tube drops and causes the current density of the tube to exceed a predetermined value. The tube 18 consists of a material, such, for example, as palladium, which is permeable to the evolved nitrogen and hydrogen gas only when heated. As the diffusion takes place over a long period, by regulating the electro-magnet 7, 8, and the heating means 25 of the rod 14, it is possible to cause the evolved feeding gas to seep slowly into the light tube. In this case the normal gas pressure in the tube 1 also is controlling and as soon as the normal gas pressure is again established the heater wire 12 30 and the heater wire 19 are both cut out of circuit whereby the large current to the gas feeding devices is interrupted and an oversupply of replenishing gas into the light tube is thus avoided.

The new heating means for a gas feeding material need not necessarily entirely supply the gas needs of the light tube. The light tube can very well have main electrodes which are gas giving electrodes made in any known manner. For example each main electrode 2, can, as in Figs. 1 40 and 3, have in the back part of same the gas evolving material mounted in a cone-shaped container 20 with an opening made therein for the escape of the evolved gas at the cone point 21 and is heated by the radiations of the electrode. In this case the main part of the feeding gases comes from the material contained in the main electrode, while the production of the correct working proportion, the lacking part of the feeding gases, is supplied by the heated gas emitting material 14. By the utilization of this new heating means, the whole gas feeding is so exact that an oversupply of gas in the tube as well as the production of an undesired higher pressure is avoided. Then too the gas producing main electrodes can now be so designed, in contrast to the former practice, that they continually and indeed even with unfavorable working conditions, for example, overloading, give off a slightly smaller quantity of replenishing than is needed. Therefore, the 60 auxiliary apparatus, consisting of the heating means 7, 8, 12, in connection with the gas evolving material 14, and dividing tube 18, through which the replenishing gas slowly diffuses into the lamp tube, can be of relatively small dimensions because of the provision of the gas evolving main electrodes in the electric discharge device itself. Such electrodes, by giving off most of the replenishing gas needed by the device in operation, save the auxiliary apparatus from frequent use, 70 which lessens the wear and tear on said auxiliary gas replenishing apparatus, and lengthens the life of the lamp tube as a whole, resulting in a compact and rugged unit and a practically steady and uniform operation of said gaseous electric 75

discharge device for a practically indefinite life. The dividing body 18 of palladium in the connecting part 17 between the light tube 1 and the offset chamber 13 can, if desired, be made in other shapes, and in other ways be mounted in the connecting part. In operation when the dividing body is heated it is pervious to the feeder gas and it is not material, whether the gas evolving substance as shown be used in the shape of solid rods or 10 loose powder or even also slabs. Furthermore, the dividing body and the gas evolving material can be heated by a single heater such as the heater wire 12.

What we claim as new and desire to secure by 15 Letters Patent of the United States, is

1. In an electric discharge device, a container, electrodes for said container, a gas filling in said container, a gas supply chamber for said con-

tainer, a gas evolving material in said chamber, a dividing body between said container and said chamber pervious to the evolved gas only when heated, and means controlled by current flowing in said container for heating said gas evolving material and said dividing body.

2. In an electric discharge device, a container, gas evolving electrodes for said container, a gas filling in said container, a gas supply chamber for 10 said container, a gas evolving material in said chamber, a dividing body between said container and said chamber pervious to the evolved gas only when heated, and means controlled by current flowing in said container for heating said gas evolving material and said dividing body.
